UNITED STATES PATENT OFFICE
REVERSING MECHANISM
Emil H. Ratzburg, Shenandoah, Pa.
Application May 4, 1942, Serial No. 441,679
1 Claim. (CL. 121—64)

This invention relates to a reversing mechanism for steam or air engines and more particularly to an upright single cylinder engine where in the cylinder is pivotally mounted and the piston thereof or its stem is connected to a power takeoff shaft, the fluid pressure being alternately admitted and exhausted at opposite ends of the cylinder. The primary object of this invention is the provision of a durable and simple construction of valve mechanism employed between the cylinder and the fluid pressure source whereby through the operation of a single hand lever, the flow of fluid pressure to and from the ends of the cylinder may be reversed and thereby bring about rotation of the power shaft in either direction desired.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawings, in which

Figure 1 is a side elevation, partly in section, illustrating an upright single cylinder engine equipped with a reversing mechanism constructed in accordance with my invention.

Figure 2 is an edge elevation illustrating the engine with the reversing mechanism applied thereto.

Figure 3 is a side elevation illustrating the reversing mechanism positioned for the operation of the power takeoff shaft in a reverse direction from that shown in Figure 1.

Figure 4 is a sectional view taken on the line 4—4 of Figure 3.

Figure 5 is a sectional view taken on the line 5—5 of Figure 3.

Referring in detail to the drawings, the numeral 5 indicates a base on which is formed a plate-like upright 6 for the support of a power takeoff shaft 7 and a cylinder 8. The power takeoff shaft is suitably journaled in the upright and is equipped at one end with a combined fly wheel and pulley 9. The other end of the shaft 7 is in the form of a crank 10 on which is journaled a stem 11 of a piston 12 reciprocally mounted in the cylinder 8. A suitable stuffing gland 13 is provided between one end of the cylinder and the stem 11 to prevent leakage. The cylinder adjacent its ends and upon one side thereof, is provided with ports 14 and 15. The purpose of the ports is to alternately admit

and exhaust fluid pressure to opposite sides of the piston 12 for the purpose of bringing about reciprocation thereof in the cylinder and which brings about rotation of the shaft 7.

The cylinder 8 is pivotally and yieldably mounted on the upright 6, as shown at 16, with the ports arranged opposite to one of the side faces of the upright and in which is formed pairs of ports 17 and 18 adapted to communicate with the ports 14 and 15 during the pivotal movement of the cylinder 8 on the upright caused by the motion of the crank of the shaft 7. The ports 17 and 18 are in direct communication with passages 19 and 20 formed in the upper portion of the upright 6 and which communicate with a valve chamber 21 formed in said upright and also communicate with exhaust ports 22 and 23 alternately opened and closed to the atmosphere by a slideable valve plate 24, the latter being provided with ports 25 which may be moved into and out of registration with the ports 22 and 23 in an alternate manner.

The valve plate 24 has slideable contact with one side face of the upright so that the ports 25 thereof may be moved to open and close the ports 22 and 23 to the atmosphere. The valve plate 24 is mounted on a valve element 26 slidably mounted in the valve chamber 21 and is provided at one end with a stop 27 and has its opposite end pivotally connected to a hand lever 28 pivoted on the upright, as shown at 29.

Formed in the valve element 26 is a passage 30 having in communication therewith ports 31 and 32. The passage 30 is in continuous communication with a fluid pressure supply port 33 at all times and to which a fluid pressure supply pipe 34 is connected.

When the valve element 26 is in one position the port 31 thereof is in communication with the passage 19 and the passage 20 is then closed to the passage 30 by the valve element. However, the valve plate 24 is then positioned so that one of the ports 25 aligns with the port 23 which places the passage 20 in direct communication with the atmosphere for exhaust purposes. It will thus be seen that the flow of fluid pressure will be into the passage 19, thence into the upper part of the cylinder to act on the piston in a downward direction. Any fluid which may be in the lower portion of the cylinder at that time is driven therefrom to the atmosphere by way of the passage 20 by the downward movement of the piston. As the piston nears its lowermost position in the cylinder, the crank acts to pivot the cylinder to bring the port 15 in communica-

tion with the passage 19 and the port 14 in communication with the passage 20, so that the fluid pressure may then enter the lower portion of the cylinder and drive the piston upwardly while the fluid in the upper portion of the cylinder may escape to the atmosphere by way of the passage 20.

If it is desired to reverse the direction of rotation of the shaft, the valve element 26 is slid by the hand lever to its other position bringing the port 32 thereof in communication with the passage 20 and the port 31 thereof out of communication with the passage 19. The flow of fluid may then be from the source to the cylinder by way of the passage 20 and the exhaust to the atmosphere from the cylinder by way of the passage 19.

From the foregoing description taken in connection with the accompanying drawings it will be seen that a very efficient, durable and practical reversing mechanism has been provided for an upright engine of the single cylinder type, wherein the power takeoff shaft may be caused to rotate in either direction whenever it is desired by a simple manipulation of the hand lever, the latter bringing about the desired movement of the valve element as well as the valve plate.

While I have shown and described the preferred embodiment of my invention, it will be understood that minor changes in construction, combination and arrangement of parts may be made without departing from the spirit and scope of the invention as claimed.

Having thus described the invention, what I claim is:

In combination with an upright single cylinder fluid pressure engine including a cylinder mounted for pivotal movement and having ports adjacent the ends thereof and a piston slideable in the cylinder between said ports and connected

to a power takeoff crank shaft, an elongated flat vertically arranged supporting plate having the cylinder pivoted thereto and rotatably supporting the crank shaft, said plate having a pair of passages and pairs of ports in direct communication therewith, said ports adapted to alternately connect with the ports of the cylinder during the pivotal movement of the latter by the rotation of the crank shaft driven by fluid pressure acting first on one side of the piston and then on the other side thereof from one of said passages during the rotation of the crank shaft in one direction and from the other passage during rotation of the crank shaft in an opposite direction, the passage not furnishing fluid pressure to the cylinder during the rotation of the crank shaft in the selected direction provides an escape for fluid pressure from the cylinder, said plate having exhaust ports in direct communication with the passages, said plate having a cylindrical valve chamber in communication with the passages and a fluid intake port connecting with said chamber and with a fluid pressure source, a cylindrical valve element manually slideable in said chamber and provided with a passage in constant communication with the intake port and having ports connecting with the latter-named passage and adapted to be alternately connected with the first-named passages by the sliding of the valve element for reversing the fluid pressure flow to the first-named passages, a valve plate connected to said valve element and slideable on the outside of the supporting plate and provided with exhaust ports to be alternately aligned with the first-named exhaust ports, and a hand lever pivotally mounted on the supporting plate and connected to the valve element for the manual sliding thereof in opposite directions.

EMIL H. RATZBURG.
